AEROPLANE

Filed Dec. 6, 1927

Inventor,

Frank L. Riffert

By *Frank L. Riffert* Atty.

UNITED STATES PATENT OFFICE.

FRANK L. RIFFERT, OF HAUBSTADT, INDIANA.

AEROPLANE.

Application filed December 6, 1927. Serial No. 238,142.

The object of this invention is to provide improvements in an aeroplane, to stabilize it and render it safe so that it may be gradually brought to earth if the engine stalls 5 when in the air; further, to facilitate retaining the plane in the air to enable minor repairs to be made; still further, to assist the engine in "taking off" from the ground by increasing the buoyant effect exerted by the 10 wings and to impart buoyancy to the body.

These, and other objects appearing from the following description, are accomplished by the provision of hollow wings or planes, compartments for the body, gas containers, 15 a pump, pipe connections, valves, and controls, enabling the pilot, or his mechanician, to permit lighter than air gas stored in the containers to be introduced in the wings or the body compartments, or both, selectively, 20 or as an entirety, to increase the lifting effect when the aeroplane is "taking off", or to increase the poise and buoyancy of the aeroplane when it is in midair as, for instance, should the engine stall and it become necessary to descend, or, to assist in supporting 25 the plane to enable minor repairs to be made.

The invention also contemplates the provision of means whereby the lighter than air gas, once it has been delivered to the hollow 30 planes and to the compartment, may be withdrawn from them and restored to the containers.

I am aware that modification may be resorted to in carrying out the invention and 35 I do not, therefore, limit it to the construction which is hereinafter described and is illustrated in the accompanying drawing, except as specified in the claims.

The accompanying drawing is a longitudinal section, partly in elevation, illustrating 40 an aeroplane provided with the present improvements.

The body of the aeroplane appears at 1 and it has upper and lower hollow planes or 45 wings 2, 3. The wings may be of metal. Struts 4 connect the wings to the body.

The body is provided with encircling compartments 5, 6, 7, 8, 9, 10 separated from each other by partitions as illustrated at 11.

Each compartment and each wing is supplied with lighter than air gas, under suitable valve control, from the series or battery of gas containers 12 preferably arranged in the region of the central part of the body 1.

The respective containers have pipes 13 connected to a main or trunk pipe 14 and each

of them has a suitable valve 15, each valve having its own control, 16, 17, 18, 19, 20, 21, 22, 23.

The pipe 14 is provided with a suitable 60 main control valve 24 which has its control 25.

The aforesaid controls are located conveniently for manipulation by the pilot or his mechanician.

There is a suitable pump 26 having a header 27 and operated by any suitable motor or engine 28. The engine 28 may be an electrically driven motor or an internal combustion engine, supplied with gasoline from 70 any suitable source and under any suitable control, whereby the pump 26 may be started or stopped at will and its operation controlled for the purpose of pumping out the gaseous contents of the containers 12 or pumping 75 back into said containers from the wings 2, 3 and the compartments 5, 6, etc. the gas which has been previously supplied thereto.

The respective compartments 5, 6, 7, etc., and the hollow wings 2, 3, are supplied with 80 the lighter than air gas from the header 27 by pipes 29, 30, 31, 32, 33, 34, 35, 36, the said pipes each having its own valve 37, 38, 39, 40, 41, 42, 43, 44. Controls for these valves are shown at 45, 46, 47, 48, 49, 50, 51, 52.

It will be seen that as great a volume as desired may be obtained from the containers 12 by operating as many of the controls 16, 17, 18, etc. as may be found to be necessary.

The gas issuing from the containers which have been opened, flows into the pipe 14 so that when the valve 24 is opened, the pump 26 may draw the gas into the header 27 for utilization in any or all of the compartments 95 5, 6, 7, etc., and wings 2, 3.

When the gas is no longer needed in the compartments and wings as aforesaid, the pump 26 may be reversed so that the gas will be drawn out of the compartments and wings 100 and forced back into the containers 12. Thus, by closing the valves 15 of said containers, the gas is retained therein for subsequent use.

Additional or "spare" gas containers may 105 be carried by the aeroplane as illustrated at 53.

What I claim is:

1. An aeroplane having independent rigid hollow wings, independent rigid compartments encircling its body, a gas container, 110 independent pipe connections from the con-

- tainer to the wing and to the compartments whereby the gas may be independently conveyed to the respective wings or compartments, a pump for withdrawing gas from 5 said container and introducing it independently into the wings and into the compartments and for returning the gas independently from any of them back to the container, when desired, and controlling means 10 for determining the direction of flow of the gas and the point to which it shall be delivered.
2. An aeroplane having a rigid hollow wing, a plurality of rigid compartments in 15 its body, a gas container, independent pipe connections from the container to the wing and to the respective compartments, independent valves for the respective pipe connections whereby communication through 20 said pipes may be independently controlled, and a reversible pump for withdrawing gas from the container and selectively introduce-
- ing it to the different compartments and wing, or for selectively returning the gas from them back to the container, at the will 25 of the operator.
3. An aeroplane having a rigid hollow wing, a plurality of rigid compartments in its body, a plurality of independent gas containers each of which has a valved inlet and 30 outlet, whereby the gas may be taken off from any one or ones of said gas containers, independent pipe connections from the respective gas containers leading to the wing and to the respective compartments, and a reversible pump for withdrawing gas from any one of the gas containers and selectively introducing it to any one of the different compartments and the wing, or for selectively returning the gas from any one of said 35 compartments or wing back to the container, at the will of the operator.

In testimony whereof I affix my signature.

FRANK L. RIFFERT.
